CLAIM

We claim the ornamental design for a window switch assembly, as shown and described herein.

DESCRIPTION

FIG. 1 is a bottom left perspective view of a window switch assembly of the present disclosure;

FIG. 2 is a top right perspective view of the window switch assembly of FIG. 1;

FIG. 3 is a bottom right perspective view of the window switch assembly of FIG. 1;

FIG. 4 is a front elevational view of the window switch assembly of FIG. 1;

FIG. 5 is a bottom perspective view of the window switch assembly of FIG. 1;

FIG. 6 is an enlarged left perspective view of area VI of the window switch assembly of FIG. 1; and,

FIG. 7 is an enlarged front elevational view of area VII of the window switch assembly of FIG. 4.

The broken lines depict portions of the article that form no part of the claimed design.

Diagonal shading using solid lines represents a front transparent surface.

1 Claim, 7 Drawing Sheets
